UNITED STATES PATENT OFFICE.

FRANK M. WOLF AND ROLLAND M. AUSTIN, OF MONROE, WISCONSIN.

TELEPHONE SYSTEM.

1,084,189.

Specification of Letters Patent.

Patented Jan. 13, 1914.

Application filed April 23, 1912. Serial No. 692,645.

To all whom it may concern:

Be it known that we, FRANK M. WOLF and ROLLAND M. AUSTIN, citizens of the United States, residing at Monroe, in the county of 5 Green, State of Wisconsin, have invented a new and useful Telephone System, of which the following is a specification.

The present invention relates to improvements in telephone systems, the primary object of the invention being the provision of 10 a novel form of means placed in each subscriber's set and especially adapted for use upon party lines, whereby the removal of the receiver from the hook will automatically signal exchange and also the various 15 parties upon the line that the receiver of a certain subscriber has been removed from the hook, this operation taking place when a called and calling subscriber are in communication or when a calling subscriber is calling the exchange.

A further object of the present invention is the provision of a novel form of signaling device included among the instruments of a 20 subscriber's set and operably connected with the receiver hook thereof, whereby the removal of the receiver from the hook and the consequent raising of the hook will actuate a device that will produce a plurality of 25 makes and breaks in the circuit which will be indicative of the special subscriber instrument, whereby other subscribers will be warned as to the subscriber that is cutting in upon the line or conversation, thus indicating to them that there is a party desiring 30 to communicate upon the line or who is listening to the conversation.

With the foregoing and other objects in view which will appear as the description 35 proceeds, the invention resides in the combination and arrangement of parts and in the details of construction hereinafter described and claimed, it being understood that changes in the precise embodiment of 40 the invention herein disclosed can be made within the scope of what is claimed without departing from the spirit of the invention.

In the drawings—Figure 1 is a diagrammatic view of a subscriber's set with the 45 present signaling device in operable relation therein. Fig. 2 is a side elevation taken from the left of the signaling device as shown in Fig. 1. Fig. 3 is a section taken on line 3—3 of Fig. 2 with the signal actuating cam in normal position when the receiver is upon the hook. Fig. 4 is a similar

view to Fig. 3 with the cam in the position it assumes after the receiver has been removed from the hook and the hook is in its uppermost position and just before the signaling device is automatically signaling. 50 Fig. 5 is a vertical central sectional view through the retarding device for preventing a too rapid operation of the signal.

Referring to the drawings the numerals 65 1 and 2 designate the line wires and more particularly of a party line telephone system. The subscriber's instrument or set S is located in the usual way and is provided with the signaling device D.

Under normal conditions the receiver hook H, having the receiver R thereupon is held down with the contact lug 3 in engagement with the contact point 4. By this means the subscriber's instrument is properly connected to the line for calling, but not for communication by speech. The contact point 4 is connected to the line 2 through the conductor 5, while the contact lug 3 of the receiver hook has the conductor 6 connected thereto, said conductor 6 being connected to one end of the spring contact 7 as shown in Fig. 1. The spring contact 7 is supported in a block of insulation 8 carried by a metal bracket 9, which 85 is itself connected to the frame of the signaling device D. The free end of the contact 7 normally is in contact with the free end of the contact plate 10, which is provided with the two lugs 11 between which 90 is journaled the roller 12, the purpose of which will presently appear. The upper end of the contact plate 10 is connected to a conductor 13 which is connected with the line wire 1, thus placing the subscriber's 95 set in calling condition with relation to the lines 1 and 2.

Ordinarily when the hook H is raised, due to the removal of the receiver R from the same, the contacts 3 and 4 will be open while the contacts at 14 and 15 will be bridged, thus throwing the transmitter T and the receiver R into the line. The conductor 16 leads from contact point 14 to the conductor 17 which is connected with the primary of the coil 18, the conductor 19 connecting the receiver R to the coil. The conductor 20, which is also connected to the coil 18, is connected to the local batteries 22. The transmitter T is connected by the conductor 21 to the local battery 22 and by the conductor 23' to the contact point 15. The

conductor 23 is connected through the resistance r to the conductor 21 and to the spring contact plate 24 carried by the metal bracket 9.

5 The free end 25 of the spring contact plate 24 is disposed to engage the outer face of the plate 10, as at 26, so that the circuit is closed at this point at the proper time when the contact plate 24 engages the 10 contact point 27 of the spring contact plate 28. The plate 28 is also supported by the bracket 9 and adjacent to the spring contact plate 24. The conductor 29 is led away from the contact plate 28, and is connected to the conductor 17 and coil 18.

15 *Signaling device.*—The signaling device D, consists of a plate or base 31, which has connected thereto and projecting therefrom the posts 32 and 32', respectively, said plate or base 31 being preferably mounted in a vertical position so as to properly support the various parts of the mechanism that are mainly actuated through gravity. A plate 33 is connected to the outer end of the two 20 posts 32 and 32', and constitutes therewith the main frame for the signaling device.

25 The shaft 34 is journaled in the plate 33 and the base 31 and has keyed upon the outer end thereof the signal actuating disk 35, which as shown is provided with the series of projections a to produce rapid intermittent opening and closing of the various contacts 27 and 25, as will later appear, while the large projections b of each series 30 will produce a long closure between contacts 27 and 25 to properly space the rapid circuit closures. These projections a and b upon the various disks 35 are arranged differently to produce a distinctive signal, so 35 that an interfering subscriber's instrument will immediately signal the calling and called subscribers' instruments, notifying them that a third party is connected to the line.

40 45 The shaft 34 has keyed or riveted thereto, a cam 36 whose periphery is provided with the depression 37, the enlargement 38 terminating in the apex 39, and the long eccentric curved portion 40, none of which 50 curved portions are concentric with the shaft 34.

55 The signaling device, when in normal position, the receiver being upon the hook, assumes the position as clearly shown in Fig. 3, wherein the pin 41 is seated within the recess of the shouldered portion 49 of the cam actuating lever or pawl 47. In order to properly mount this pawl 47, a pin 42 is connected to the base plate 31 and has 60 mounted thereon the sleeve 43, which carries the actuating arm 44, said actuating arm 44 being connected to the receiver hook H by means of a rod 45. Disposed at substantially right angles to the operating arm 44 is a lug or projection 46 which has pivoted

thereto the cam actuating pawl or arm 47, which as clearly shown in Figs. 3 and 4 is provided with the pointed end 48, with the intermediate shouldered portion 49, and the shouldered portion 50, the spring 51 being 70 connected to the arm 44 and the inner free end of the pawl 47, so as to normally raise the outer free end 48 thereof into the position as shown in Fig. 3.

75 With the parts normally in the position as shown in Fig. 3, the receiver being upon the hook H, the removal of the receiver from the hook will permit the usual rising of the hook which will cause the rod 45 to rise and actuate the pawl 47 moving the same from 80 the position as shown in Fig. 3 to that shown in Fig. 4, while in order to automatically actuate the shaft 34 to rotate the signaling disk 35, a spring or gravity actuated device is provided for completing the movement of 85 the disk 35 to automatically indicate to the other subscribers and the exchange that the receiver in the particular subscribers' instrument has been lifted from the hook. The position of the signaling disk 35 when in 90 normal position is shown in Fig. 1, but when the shaft 34 has been rotated to assume the position as shown in Fig. 4, the roller 12 is in contact with the surface d at its juncture with the first projection a to the left as 95 shown in Fig. 1.

95 The mechanism for automatically operating the signaling disk consists of the vertically slidable rod 52 which is provided with the inverted U-shaped end 53 and with the 100 short terminal 54, the portion 52 being slidably mounted in the posts or standards 32 and 32' respectively, while the terminal 54 is slidably mounted in a post 55 carried by the base plate 31. Connected upon the lower 105 end of the rod 52 is a weight 56, which automatically moves the rod 52 from the position, as shown in Fig. 4, to the position as shown in Fig. 3. In order to prevent a too rapid descension of the rod 52 after the same has been raised from the position as shown in Fig. 3 to that shown in Fig. 4, a plunger 57 is formed upon the end of the rod 54 and is mounted for reciprocation within the cylinder 59, an air tight gasket 58 being carried upon the inner end of the plunger 57, as clearly shown in Fig. 5. This cylinder or dash pot 59 is provided with the air escape and admission port 60 and is supported in the post 61 carried by the base plate 31. 110

115 120 Mounted upon the rods 52 and 54, below the posts 32' and 55, is a tube 62 which by means of a pin 63 is rigidly secured to the rods so as to move therewith, in its vertical movement, up and down. One end of the rod 63 has connected thereto a spring 64, the other end of said spring 64 being connected to a post 65 carried by the plate 31, said spring exerting a tension downwardly to assist the weight 56 in properly moving the 125 130

rod 52 and the sleeve 62 from the position as shown in Fig. 4 to that shown in Fig. 3. This spring, however, may not be necessary but is simply employed as an auxiliary to the weight 56, or the weight may be dispensed with and the spring only used.

A pin 66 connected to and carried by the sleeve 62, has mounted thereon the anti-frictional roller 67 which is in engagement 10 at all times with the periphery of the cam 36 so that when the pawl is moved from the position as shown in Fig. 3 to that shown in Fig. 4, the roller 67 will ride from the recess 37 over the cam surfaces 38 up to the 15 highest point of the apex 39 of the cam, at which time the pawl 47 will be released from the pin 41 of the cam and the spring 64 and weight 56 will exert a tension to move the sleeve 62, and as the tendency of the cam is toward the direction of the arrow in Fig. 4, the roller will ride upon the cam surface 40 and impart rotation to the shaft 34 and consequently the signaling disk 35. This action will cause the projection *a* of the 20 first series to move the free end of the contact spring 10 forwardly, closing the contact between the free ends 25 and 26, this action thus providing an intermittent make and break at the points 27 and 25 and producing a similar click in the receivers of the 25 various subscribers' instruments, or the receivers of the calling and called subscribers when in communication. The notches *a*—*b* of the signaling disks 35 may be formed with a different combination, according to the subscriber's set, so that no 30 two sets will produce the same signal in the line. It will thus be seen that after breaking contact at the spring contact 7, that the moving periphery of the signaling disk 35 will actuate the free end of the contact plate 11 to execute a series of contacts and breaks at 25 and 27 and consequently in the local battery of the subscriber's set, closing the 35 primary winding in the coil 18 and shunting the transmitter by a suitable resistance *r*, thus causing a click audible in any receiver on the line. An electrical diagram for producing the desired effect is clearly 40 shown in Fig. 1 although it is evident that many modifications of the invention may be made whereby the signaling disks may produce the desired effect to indicate to the called and calling subscriber and also to 45 central or the exchange the exact subscriber interfering with the conversation while calling the same. The shoulder 50, of the arm 47 is a means to prevent the defeat of this system. Should the switch hook *H*, be depressed only far enough to break the bridge 50 points 14—15, and be again raised, the shoulder 50 will engage the pin 41, causing the disk 35 to rotate far enough to raise the roller 12 by contact with the peripheral 55 projection *d*' and thereby to break contact

between plates 7 and 10, which contacts, due to the disk 35 remaining at such position will remain broken until the switch hook *H* is sufficiently depressed to allow the shoulder 49 to engage the pin 41.

As shown in Fig. 1, the contact 7 of the spring 8 with the spring 10 is broken as soon as the disk 35 is moved from the position shown in Figs. 1 and 3 to that shown in Fig. 4. The roller 12, as seen in Figs. 1 and 3 rests in the deeper depression of the periphery of the disk 35, permitting the springs 7 and 10 to contact, only when the parts are in the position as shown in Figs. 1 and 3.

While herein the invention is described in detail, and a combination embodying various features is illustrated, which may at times be used to advantage, it is not the desire or intention of claimants to be limited to the particular arrangement shown, or to an arrangement embodying the various auxiliary features, except as particularly pointed out in the appended claims.

What is claimed is:

1. In a telephone system, a sub-station having a receiver, a transmitter, a receiver hook, a pair of normally closed contacts in the line circuit, a local battery circuit having a switch therein, a rotary device to automatically actuate the switch, and means operably connected to the receiver hook and said rotary device to actuate the device when the receiver is fully removed from the hook and to operate the switch to intermittently open and close the battery circuit and signal to the line, said contacts being held open due to the receiver hook being slightly raised.

2. In a telephone system, a sub-station having a pair of normally closed contacts in the line circuit, a local battery circuit, a receiver, a transmitter, a receiver hook, a switch in the local battery circuit, a rotary device to automatically actuate the switch, and a pawl and ratchet device operably connecting the hook to the rotary device, whereby the removal of the receiver from the hook will permit the actuation of the device to intermittently open and close the switch to signal the line, a slight elevation of the hook actuating the rotary device to hold the contacts open and until the hook is sufficiently depressed to permit the full engagement of the pawl and ratchet device with the rotary device.

3. In a telephone system, a subscriber's set having a normally closed switch in the line circuit, a local battery circuit, a receiver, a transmitter, a receiver hook and a pair of contacts in the local battery circuit, a rotary device to automatically actuate the contacts of the local battery circuit, and means operably connected to the receiver hook and said rotary device for actuating the device when the receiver is fully removed from the hook to actuate the contacts of the local battery

circuit to intermittently open and close the battery circuit and signal to the line, and when the receiver hook is slightly raised to actuate the device to hold the switch open 5 until the hook is sufficiently depressed to permit the full engagement of the operating means with the rotary device.

4. In a telephone system, a sub-station having a local battery circuit, a receiver, a 10 transmitter, a receiver hook, a switch in said circuit, a rotatable shaft, a disk mounted upon the shaft and in coöperable relation with the switch, a cam mounted on the shaft, coöperable means carried by the 15 cam and the receiver hook for rotating the shaft and disk through the receiver hook when the hook is raised, the rotation of the disk intermittently opening and closing the circuit to signal the line, a gravity biased device operably connected to the cam and forming a locking device therefor when the receiver is upon the hook and an actuating 20 device for the shaft and disk after the cam has a partial rotation imparted thereto due to the elevation of the hook, and means for retarding the gravity action of said device and insuring an even actuation of the disk. 25

5. In a telephone system, a sub-station having a local battery circuit, a receiver, a

transmitter, a receiver hook, a switch in said circuit, a rotatable shaft, a disk mounted upon the shaft and in coöperable relation with the switch, a cam mounted on the shaft, coöperable means carried by the cam and the receiver hook for rotating the shaft and disk through the receiver hook when the hook is raised, the rotation of the disk intermittently opening and closing the circuit to signal the line, a gravity biased device operably connected to the cam and forming a locking device therefor when the receiver is upon the hook and an actuating 40 device for the shaft and disk after the cam has a partial rotation imparted thereto due to the elevation of the hook, and means for retarding the gravity action of said device and insuring an even actuation of the disk. 45

In testimony that we claim the foregoing as our own, we have hereto affixed our signatures in the presence of two witnesses.
